UNITED STATES PATENT OFFICE.

JAY GOULD WATTS, OF CRICHTON, LOUISIANA.

DOOR-OPERATING MEANS.

1,256,404.

Specification of Letters Patent. Patented Feb. 12, 1918.

Application filed May 17, 1916. Serial No. 98,153.

To all whom it may concern:

Be it known that I, JAY G. WATTS, a citizen of the United States, residing at Crichton, in the county of Red River and State 5 of Louisiana, have invented new and useful Improvements in Door-Operating Means, of which the following is a specification.

This invention relates to a door operating mechanism primarily designed for use in 10 connection with a sliding door or the like.

The invention aims to provide a mechanism of the above mentioned character, embodying among other features a platform or the like disposed in close proximity to the 15 door and associated therewith in the manner, to cause the said door to assume an open position when the platform is depressed, together with means for automatically returning the door and the various 20 parts of the mechanism to normal position, upon release of said platform.

With these and other objects in view which will appear from the following description, as the latter is read in connection 25 with the accompanying drawings, the invention resides in the construction, combination and arrangement of parts as defined in the claims.

In the drawings forming part of this 30 specification like numerals of reference indicate similar parts in the several views and wherein:—

Figure 1 is a front elevation partly in section showing the door in closed position.

Fig. 2 is a similar view showing the door 35 in its open position.

Fig. 3 is a vertical transverse sectional view.

Fig. 4 is a horizontal sectional view.

Fig. 5 is a detail sectional view of the 40 drum.

Fig. 6 is a detail view of the platform.

Before entering into a detail description of what is herein shown, I desire to have it 45 understood that I do not limit myself to this particular construction, and that such changes may be resorted to when desired as fall within the scope of what is claimed. It might further be stated that a door controlled by means of the invention may be used either up or downstairs in a building, and is also susceptible for use as a driveway gate of the like, but in any instance the door is automatically controlled in its movements in a manner to be hereinabove described.

Upon reference to the drawings in detail A indicates the floor of a building, and B the wall provided with the usual door opening C. During the construction of the 60 building, or in other words the wall B, a door frame indicated at 10 is built between the partitions of the wall, and includes parallel side members 11 and a connecting top piece 12. The door 13 is supported upon the 65 frame for sliding movement, for which purpose the top piece 12 is provided with a guideway 14 through which the upper portion of the door projects, the latter being provided with suitable hangers 15 upon 70 which is journaled a plurality of rollers 16 adapted to rest upon and move from the upper surface of the top piece 12. Of course one of the side members 11 is also slotted to permit of the door being opened, 75 during which time the latter is moved within the space between the partitions of the wall B. When the door is moved in an opposite direction the jamb thereof engages the opposite member 11 and not only serves 80 to limit the closing movement of the door but also provides a tight joint between the parts. The frame 10 may be constructed to accommodate one or more doors, one of which may be a screen door, the doors being arranged one in advance of the other. When two doors are employed as herein 85 illustrated, the top piece 12 of the frame is of course provided with spaced parallel guideways 14.

The floor A at a point in close proximity to the door, is provided with an opening 17, which may be of any suitable dimensions, having the edges thereof beveled as at 18. Fitted within this opening and adapted to 90 lie flush with the surface of the floor is a platform, preferably in the nature of an enlarged block 19. Depending from the block 19 is a rod 20 slidably fitted in a bearing 21, and having its lower end operatively associated with the adjacent end of a horizontally disposed arm 22 pivoted adjacent the end connected with the rod 20 upon the bearing 21. Disposed a requisite distance to one side of the rod 20 is a base 23, from which 95 rises spaced parallel standards 24 having journaled therein a horizontally disposed shaft 25. Fixed upon the shaft 25 for rotation therewith is a drum 26, and interposed between the heads 27 thereof is a circumferential series of spaced parallel pins 28 adapted to be engaged by the teeth 29 of

the arcuate shaped member 30 carried upon one end of the arm 22, for the purpose of imparting a rotary movement to the drum in one direction when the arm 22 is elevated 5 simultaneously with the depression of the platform 19. While it is herein specifically stated that the drum is provided with pins 28, it may be provided with a toothed surface or otherwise constructed to coöperate 10 with the arcuate shaped member 30 for the purpose mentioned. Secured to the outer side of each of the heads 27 of the drum, is a pulley 31 over which is trained a continuous cable 32, the latter being secured to the 15 drum. The cable has a portion thereof extended transversely above the frame 10, and is trained over a plurality of guide pulleys 33 suitably arranged upon the frame, one lead of the cable being secured to the upper 20 edge of the door so as to move the latter in opposite directions to either opened or closed position, when the drum is rotated in one or the other direction. The cable has its opposite ends connected by suitable detachable 25 fastening means indicated at 34, to permit of the cable being used in connection with either of the pulleys 31 and connected with either one or the other of the doors shown. It is to be understood of course that but one 30 door is operated at a time, and the door not in use is moved to an opened position out of the way. The door is provided with any suitable form of lock or latch mechanism, preferably key operated, which is mounted 35 upon the frame 10.

In practice, when weight is placed upon the platform 19 thereby depressing the latter, the arm 22 is moved about its fulcrum elevating the arcuate shaped member 30, 40 which as above stated coöperates with the drum to partially rotate the latter, and through the medium of the cable 32 the door is slid to an opened position. A suitable weight 35 is secured to one of the 45 pulleys adjacent the periphery thereof, thus unbalancing the drum, so that when the pressure or weight is removed from the platform 19, the movement of the drum is automatically reversed through the medium 50 of the weight 34, and the weight of the arm 22, whereupon the drum, arm 22, and platform 19 return to their normal position. During this movement of the parts a pull 55 on the cable is exerted in an opposite direction from that exerted during the opening of the door, thereby sliding the door in the reverse direction to its closed position. The base 23 is provided with a recess or pocket 60 36 adapted to receive the lower end of the arcuate shaped member 30, and this pocket is filled with sand or other suitable material to eliminate noise which would otherwise result from the drop of the arcuate shaped member 30 to normal position. It will be 65 manifest that by reason of this construction

should the cable for any reason break, while the door is in operation, the latter will be instantaneously brought to a standstill, thereby eliminating the danger of anyone being hurt.

As clearly illustrated in Fig. 6 the block 19 has its upper edges beveled as at 37 to correspond with the beveled edges of the opening in the floor A, which serves to limit the return movement of the block 19, and 70 also provides for a proper fit between these parts. The block also has one of its sides inclined as at 38 to provide a clearance for the movement of the arm 22, as well as to permit the rod 20 to be arranged as far as possible 75 toward the adjacent end of the arm 22, with the saving of space, and also allowing the arm to have a maximum degree of leverage to operate the door with a very slight depression of the platform 19. It might here be 80 stated that in constructing the wall B means should be provided to permit the doors to be 85 quickly and easily removed or positioned in place as the occasion may require.

It is believed that from the foregoing description the nature and advantages of the invention will be readily apparent without requiring a more extended explanation and therefore the same has been omitted.

What is claimed is:—

1. A door operating means comprising in combination with a sliding door, a drum mounted for rotation, a cable connected with the door and trained over the drum for opening the door upon rotation of the drum 100 in one direction and closing the door upon reverse rotation of said drum, a movable member normally lying flush with the surface and adapted to be depressed when weight is brought to bear thereon, a horizontally disposed rod pivoted beneath said member for vertical swinging movement, one end of said rod being connected with the member whereby the rod is adjusted upon depression of said member, an arcuate 110 shaped toothed element carried by the opposite end of said rod and engageable with the drum to rotate the latter in a direction to open the door when said member is depressed, and a weight carried by the drum to 115 unbalance the latter and automatically return the drum and the aforementioned parts to their normal position.

2. A door operating means comprising in combination with a sliding door, a drum 120 mounted for rotation, a cable connected with the door and trained over the drum whereby said door is opened upon rotation of the drum in one direction and closed upon reverse rotation of said drum, a movable member operating through an opening in the floor or surface and adapted to be depressed when weight is brought to bear thereon, a horizontally disposed pivot rod arranged beneath the member and connected therewith 130

to be moved about its pivot when said member is depressed, a plurality of spaced transverse pins forming part of said drum, an arcuate shaped rack bar carried by one end 5 of the rod and coöperating with said pins to rotate the drum when the member is depressed in a direction to open the door, a weight carried by the drum for reversing the movement of the latter and returning 10 the same and the aforementioned parts to

normal position when pressure is removed from said movable member, and means for limiting the adjustment of said parts in this direction.

In testimony whereof I affix my signature 15 in presence of two witnesses.

JAY GOULD WATTS.
